UNITED STATES PATENT OFFICE.

HENRY HORAN, OF EAST ORANGE, NEW JERSEY, ASSIGNOR TO HARTFORD CARPET COMPANY, OF HARTFORD, CONNECTICUT.

DESIGN FOR CARPET.

SPECIFICATION forming part of Design No. 12,042, dated November 30, 1880.

Application filed September 18, 1880. Term of patent 3½ years.

To all whom it may concern:

Be it known that I, HENRY HORAN, of East Orange, in the county of Essex and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The figure A is a rectangular figure, having within it an ornamentation of smaller rectangles and of a spray of flowers. Upon one side of the figure A appears the figure V, also rectangular, with a band running across it. Projecting from the other side of the figure A is the figure O, consisting of a half-rosette, resembling the half of a wheel. This overlaps the figure B, which is rectangular and ornamented with leaves and flowers, and adjoins the figure G, a rectangular figure embellished with ornamental figures.

The figure I is a parallelogram adjacent to the figure A, and to the figure N, which is rectangular and ornamented with fern-like leaves.

The figure O is a bunch of flowers, buds, and leaves, placed within a triangular surrounding border, of which the figure P forms an apex.

The figure D is also a bunch of flowers and leaves placed within a square border.

The figure E is an ornamented band between the figure O and the figure F, which last consists of flowers and leaves within a triangular border.

The figure S is a band forming one side of this triangular border, and having upon it scalloped ornaments.

The figure H consists of an ornamented band, over which projects a stem with buds thereon.

The figure Q is a broad ornamented band running diagonally from the figure H to the figure K, and separated from the figure K by the smaller band T, which is ornamented with fern-like branches. From one side of this fig-

ure Q projects the semicircular figure J, ornamented with flowers and leaves, and partly overlapping the irregular figure L, ornamented with branches and flowers, and also overlapping the figure W, ornamented with diagonal bands.

A diagonal band, U, separates the figure L from the figure K, which last is a segment of a circle ornamented with branches and a patterned background, and which is overlapped by the figure M, consisting of a bunch of flowers within a square border.

The figure F consists of a bunch of spreading flowers, leaves, and buds, occupying a space bordered by the figures S, K, and A.

I claim—

1. The design for carpets, consisting of the figure A, substantially as shown.
2. The design for carpets, consisting of the figure B, substantially as shown.
3. The design for carpets, consisting of the figure G, substantially as shown.
4. The design for carpets, consisting of the figure O, substantially as shown.
5. The design for carpets, consisting of the figure V, substantially as shown.
6. The design for carpets, consisting of the figures V, A, O, and I, substantially as shown.
7. The design for carpets, consisting of the figure H, substantially as shown.
8. The design for carpets, consisting of the figure C, substantially as shown.
9. The design for carpets, consisting of the figure D, substantially as shown.
10. The design for carpets, consisting of the figure M, substantially as shown.
11. The design for carpets, consisting of the figure Q, substantially as shown.
12. The design for carpets, consisting of the figure J, substantially as shown.
13. The design for carpets, consisting of the figures Q, J, and W, substantially as shown.
14. The design for carpets, consisting of the figures R, E, Q, and S, substantially as shown.
15. The design for carpets, consisting of the figure F, substantially as shown.
16. The design for carpets, consisting of the figure K, substantially as shown.
17. The design for carpets, consisting of the figure L, substantially as shown.

18. The design for carpets, consisting of the figure N, substantially as shown.

19. The design for carpets, consisting of the figures T, U, and K, substantially as shown.

5 20. The design for carpets, consisting of the figures P, C, and R, substantially as shown.

21. The design for carpets, consisting of the

figures A B C D E F G H I J K L M N O P
Q R S T U V W.

HENRY HORAN.
